Application November 3, 1938, Serial No. 238,694
In Sweden November 13, 1937

5 Claims. (Cl. 144—268)

In barking drums (bark removing drums) as hitherto known, which are mounted on guayac wood blocks or blocks from other suitable material arranged in a vat filled with water, the disadvantage is met with that any sand, gravel and other rubbish present in the water deposits between the guayac wood blocks and the slide rings of the barking drum proper running in contact with the same, so as to cause great wear of the guayac wood blocks as well as of the slide rings.

But also disregarding whether such particles enter between the contacting surfaces of the drum and the parts carrying the same, the wear becomes great on account of the great weight of the drum.

The present invention refers to arrangements aiming at reducing or at practically eliminating the wear of the parts in question, even in such cases where the drum is carried, entirely or in part, by means of rollers or the like.

The accompanying drawings illustrate a plurality of embodiments of the invention. Figs. 1-3 show the first embodiment, Fig. 1 showing a longitudinal section of the barking drum, Fig. 2 a cross section thereof, and Fig. 3 a detail to a larger scale. Fig. 3a is a detailed view of a modification of the upper end of the arc-shaped drum supporting blocks of Fig. 2.

Fig. 4 shows a modification of the detail according to Fig. 3.

Fig. 5 shows a barking drum provided with another embodiment of the invention, in elevation and partly in section on line V—V in Fig. 6. Fig. 6 shows a section on line VI—VI in Fig. 5.

According to Figs. 1-4, the contrivance consists of two or more rings 1 rigidly arranged about the drum A, said rings being provided with sliding surfaces 2 running on guayac wood rails 3 shaped on the lines of circular arcs, said rings being secured, for instance, each in a rail 4 inserted into the bottom of the vat B, these rails 4 being also shaped on the lines of circular arcs. Each rail 3 is preferably made integral. To bring the drum A into rotation, there is secured a toothed ring 8 to the same, which ring is driven by means of a pinion 9.

The rails 3, the sliding surfaces of which adjoin the sliding surfaces 2, have such an extension in the peripheral direction that the end portions 10 and 11 thereof will be located above the water level 14, the entry of gravel, sand, bark and the like between the sliding surface 2 of the ring 1 and the sliding surface 5 of the guayac wood rail 3 being rendered more difficult.

Provided in the sliding surface 5 of each rail 3 is a groove 6 communicating with a hydraulic pump or the like 26 through a pressure conduit 7 for water or other liquid. The object of this groove 6 is that the pressure liquid forced into the same shall bring about an upwardly directed pressure on the sliding surface 2 as well as scavenging of the sliding surfaces. In order that such scavenging of the sliding surfaces shall be enabled to take place the arrangement must of course be such that pressure liquid departs from the grooves 6 to the vat past the sliding surfaces. No particles of bark, sand and so forth can then enter between the sliding rails 3 and the sliding surfaces 2 of the drum rings. Simultaneously as liquid is supplied to the vat and scavenges the sliding surfaces the upward pressure thus obtained on the rings 1 reduces the bearing pressure on the guayac wood sliding surfaces 5 to an appreciable extent, whereby the friction losses will also be reduced. With suitably selected dimensions for the grooves 6 and a reasonably large quantity of the liquid forced in and a reasonable pressure thereon, a great portion of the weight of the drum may practically be carried by the pressure medium, whereby the consumption of power is materially lessened. The arrangement in question for unloading the pressure of the drum on the parts supporting the same may also be applied in barking drums adapted to be driven and supported in some other way, for instance in barking drums bearing at the bottom or at the top on rollers, as shown in Figs. 5 and 6. It is possible, for example, to provide the drum with a plurality of rings extending adjacent to other annular stationary members, the construction being then such that one or more intermediate spaces will be produced between the rings rotating with the drum and the rigid rings, which spaces may be brought into communication with a pressure conduit.

Thus according to the invention one or more intermediate spaces between surfaces arranged on the drum, on the one hand, and surfaces of parts beside the drum not participating in the rotary movement, on the other hand, are in communication with a conduit for a pressure medium, the arrangement being such that, when a pressure medium (i. e. liquid, air, steam or other gaseous medium under pressure) is introduced into this or these intermediate spaces, the pressure of the drum on the supporting part or parts supporting the same is reduced. It will be understood that the grooves or spaces for the

pressure medium may be provided in the rotary sliding surface instead of in the stationary surface, or in both. On one or both rings 1 may be arranged a rigid guide edge 12 and a guide flange 13 adapted to be adjusted upon wear, an axial mounting of the drum being thus obtained, as shown in Fig. 4. The operation of the drum may preferably be arranged in a manner such that the rotary movement of the pinion 9 has such a direction that the tooth pressure of the pinion 9 and the tooth ring 8 results in an upwardly directed force, which tends to lift the drum from the guayac wood slide rails 3.

In special cases, it may be sufficient, if only the one ends of the sliding surfaces (depending on the direction of rotation of the drum) reach above the water level in the vat.

Preferably, the sliding surface extends along a great portion, preferably between 120 and 180° of the periphery of the drum, as shown in the drawings.

According to the embodiment shown in Figs. 5 and 6, the mounting and supporting members for the drum A consist of two pairs of rollers 29 provided on the lower side of the drum and co-operating with the rings 31 secured to the drum. Near each end of the drum there is provided a contrivance serving with the aid of a pressure medium to reduce the pressure of the drum on the rollers. This contrivance consists of a ring 34 secured on the drum, an intermediate space 37 being provided between said ring 34 and a rail or the like 36 arranged beneath the drum and secured to the foundation or to the water container B, which intermediate space is intended to serve as a pressure space for a pressure medium, such as liquid. The rail 36 is provided with lateral flanges 38 bearing tightly against the edge sides 39 of the ring 34 or preferably by means of an intermediate packing. The rail 36, which is seen to lie in the water in the container, extends, however, with its end portions for a distance above the water level, and it is provided with inwardly projecting flanges or the like 40 at or near the ends thereof, which flanges do not, however, reach as far as to the ring 34. The pressure space 37, to which the pressure medium is supplied through the conduit 41, is, in other words, restricted at the ends of the rails 36, so that the resistance to the exit of the pressure medium from the pressure space is increased at these end portions.

If the pressure space is made very narrow, that is to say, if the distance between the ring 34 and the rail 36 is very small, for instance all over not greater than the distance between the flanges 40 and the ring 34, obviously no such flanges are required.

Thus it should be readily understood that when liquid, steam or other gaseous medium is introduced into the pressure space 37 through the conduit 41, the pressure medium has a raising effect on the drum, so that the pressure of the latter on the rollers 29 is reduced. As will be seen from the drawings, the drum never rests on the rail 36, not even when the pressure in the pressure space is relieved. Since the rollers are the only carrying members for the drum, the latter consequently only has to overcome rolling friction (disregarding the very small friction between 38 and 34) when rotating, but such rolling friction is reduced to a considerable extent, or is eliminated almost altogether, when the pressure medium is caused to act in the pressure space 37.

Thus the rollers will be saved in an appreciable degree, so that the risk of their becoming destroyed is believed to be altogether eliminated, while their life is enormously increased.

5 If liquid be used as pressure medium, it is preferred to employ a warmed-up liquid, so that, perhaps, no other spraying of warm liquid over the timber need be undertaken beyond that escaping from the pressure spaces.

10 If steam or other gaseous medium of a high temperature, such as hot air, be used as pressure medium, the latter may, on having escaped from the pressure space (pressure spaces), be utilized to heat the liquid in the container. In the embodiment according to Figs. 1 and 2, for example, the hot pressure medium may then escape through fine holes or apertures directly into the water in the container beneath the surface of the water.

15 The restriction of the pressure spaces at the end portions of the rails or blocks in the various embodiments should, as a rule, be such that the intermediate space between the throttling flanges 40 and the opposite surfaces will only be a fraction of a millimetre, for instance one or a few tenths of a millimetre. If desired, the flanges may also bear tightly against the opposite surfaces in all of the embodiments shown, and fine outlet openings for the pressure liquid may be arranged in other places of the walls of the pressure space. Even if no special arrangements be undertaken to bring about such exit openings, the pressure medium is believed to find its way out of the pressure space between surfaces of the walls limiting the pressure space, such surfaces moving relatively to each other. By the fact that the rings or the like on the drum, which form the limiting surfaces of the pressure spaces, have a small extension in the longitudinal direction of the drum, the bark may, as ordinarily in drums of the type illustrated, escape between the rods, beams or the like, out of which the drum body proper is composed.

20 What we claim is:

1. In an apparatus for removing bark from wood, the combination of a rotatable barking drum to receive the wood to be barked, a tank for retaining a liquid in which said drum is partially immersed, said drum having perforated sides and carrying spaced tires arranged about and rotating with the drum, means for supporting said drum in said tank including arc-shaped supporting members conforming to said tires, said members having bearing surfaces in said liquid in sliding contact with said tires, pressure spaces between said surfaces and said tires, and means for supplying fluid under sufficient pressure to said spaces to materially reduce friction losses and to prevent entrance of dirt from said liquid into said bearing surfaces.

2. In an apparatus for removing bark from wood, the combination of a rotatable barking drum to receive the wood to be barked, a tank for retaining a liquid in which said drum is partially immersed, said drum having perforated sides and carrying spaced tires arranged about and rotating with the drum, arc-shaped supporting members conforming to said tires for sustaining the weight of said drum, said members having bearing surfaces in said liquid in sliding contact with said tires, one end of said bearing surfaces being located at least up to the level of the liquid in the tank, pressure spaces between said surfaces and said tires, and means for supplying fluid under sufficient pressure to said spaces to

materially reduce friction losses and to prevent entrance of dirt from said liquid into said bearing surfaces.

3. In an apparatus for removing bark from wood, the combination of a rotatable barking drum to receive the wood to be barked, a tank for retaining a liquid in which said drum is partially immersed, said drum having perforated sides and carrying spaced tires arranged about and rotating with the drum, arc-shaped supporting members conforming to said tires for sustaining the weight of said drum, said members having bearing surfaces in said liquid in sliding contact with said tires, the ends of said bearing surfaces being located at least up to the level of the liquid in the tank, pressure spaces between said surfaces and said tires, and means for supplying fluid under sufficient pressure to said spaces to materially reduce friction losses and to prevent entrance of dirt from said liquid into said bearing surfaces.

4. In an apparatus for removing bark from wood, the combination of a rotatable barking drum to receive the wood to be barked, said drum having perforated sides and being provided with tires rotating with the drum and having bearing surfaces, a tank adapted to contain a liquid in which said drum is partially immersed, a supporting device for sustaining the weight of the drum, said device being located in said tank and having arc-shaped wood members having bearing surfaces in said liquid in sliding contact with

said tires, the last-named bearing surfaces which present a large extension in the peripheral direction, at a maximum of 180°, extending from a point located above the level of the liquid in the tank on one side of the drum to a point located above said liquid level on the other side of the drum, and means for supplying fluid under sufficient pressure to said spaces to materially reduce friction losses and to prevent entrance of dirt from said liquid into said bearing surfaces.

5. In an apparatus for removing bark from wood, the combination of a rotatable barking drum to receive the wood to be barked, a tank for retaining a liquid in which said drum is partially immersed, said drum having perforated sides and carrying spaced tires arranged about and rotating with the drum, arc-shaped supporting members conforming to said tires for sustaining the weight of said drum, said members having bearing surfaces in said liquid in sliding contact with said tires, pressure spaces between said surfaces and said tires, and means for supplying fluid under sufficient pressure to said spaces to materially reduce friction losses and to prevent entrance of dirt from said liquid into said bearing surfaces, said pressure spaces being constricted at the ends.
